[57] ABSTRACT

A low temperature liquified gas storage tank having an outer shell and an inner wall formed by a plurality of multi-layer panels, each panel including at least one interior liquid-tight membrane layer protected from excessive thermally induced stresses by an exterior heat shock absorbing layer of plywood or fibrous material which forms the inner wall surface of the tank. A symmetrical arrangement of the membrane layer or layers with respect to the cross-sectional center of the panel prevents warping thereof under thermally induced stress.

FIG. 7

LOW TEMPERATURE LIQUEFIED GAS STORAGE TANK

SUMMARY OF THE INVENTION

The present invention relates to a low temperature liquefied gas storage tank, and more particularly to such a storage tank wherein plywood panels subjected to liquid-tightness treatment are used as an inner tank wall applied to the inner side of the rigid outer shell of the tank.

In general, since plywood has a low coefficient of expansion or contraction in connection with temperature change, it is used as a wall material for low temperature liquefied gas storage tanks subjected to temperature change. However, since plywood is lacking in liquid-tightness, it is necessary to render it liquid-tight when it is used as an inner wall material for the tank. To this end, a low temperature resistant metal sheet such as of aluminum or stainless steel, or a synthetic resin film, has been bonded to the surface of plywood. When such a plywood wall construction, having a metal sheet or synthetic resin film bonded to the plywood surface, receives a low temperature liquid, there will be a violent shearing force acting on the interface between the sheet or film and the plywood. This is because the thermal expansion coefficient of the metal sheet or synthetic resin film is much greater than that of the plywood, so that a high heat shock is produced in the metal sheet or synthetic resin film. In the case of aluminum, for example, the thermal stress is of the order of 50-60 times that of plywood. Therefore, where plywood having a metal sheet or synthetic resin film bonded to the surface thereof is used as a tank wall material for direct contact with a low temperature liquid, there is the danger of causing the separation and cracking of the metal sheet or synthetic resin or of causing the warping of the plywood as a result of the shearing force acting in the described manner. Further, since the metal sheet or synthetic resin film is intended for providing liquid-tightness, not for supporting the pressure of low temperature liquid, the thickness thereof may be as thin as the order of 0.3-0.1 mm. Therefore, when plywood having such a thin metal sheet or synthetic resin film exposed on the plywood surface is used to form a tank wall, there is a disadvantage that it is liable to be damaged by contact with other objects during the tank wall forming operation.

For the above reasons, it is seen that a low temperature liquefied gas storing tank constructed of plywood having a metal sheet or synthetic resin film bonded to the surface thereof has drawbacks due to thermal factors and mechanical damage.

The low temperature liquefied gas storage tank of the present invention overcomes the problems described above, and comprises an outer tank shell, a plurality of panels mounted inside of and spaced from the outer shell to form an inner wall of the tank, and a heat insulator interposed between the outer shell and inner wall; wherein said panels are each of multi-layer construction and include at least one interior liquid-tight membrane layer and an exterior heat shock absorbing layer forming the inner wall surface of the tank.

Other features and advantages of the invention will appear from the description to follow of the embodiments thereof shown in the accompanying drawings.

DESCRIPTION OF THE DRAWINGS

FIG. 1 is a schematic sectional elevation of a tank installed on the ground;

FIG. 2 is a schematic sectional elevation of a tank installed in a ship;

FIG. 3 is an enlarged perspective view in transverse section through the wall of the tank showing one of the embodiments of the invention;

FIG. 4 is an enlarged sectional view through a portion of the inner wall of a tank showing another embodiment of the invention;

FIGS. 5 and 6 are perspective views each showing other forms of liquid-tight wall panel constructions of the invention; and,

FIG. 7 is a graph explanatory of heat shock absorbing effects.

DESCRIPTION OF THE PREFERRED EMBODIMENTS

As shown in FIGS. 1 and 2, this type of tank is formed usually of a tank body A and a secondary protective wall B for prevention of the outflow of a low temperature liquid in the event of damage to the tank body. In the following embodiment, only the secondary protective wall will be described, but the secondary protective wall may, of course, be employed as a liquid storage tank. Further, in one case the tank is built on the ground as shown in FIG. 1 and in another case it is built in a ship as shown in FIG. 2.

The inner wall of the tank is constructed by connecting a number of rectangular liquid-tight panels end-to-end.

Multi-layer liquid-tight panels 1 shown in FIG. 3 are each constructed by bonding liquid-tight membrane layers 4a and 4b of low temperature resistant metal to both sides of a plywood core 3, consisting of a plurality of veneers 2, and then bonding veneers 5a and 5b to the surfaces of said liquid-tight membranes 4a and 4b to serve as heat shock absorbing layers. The veneer 5a of the panel 1 which will be in direct contact with low temperature liquid is cut away in advance over a predetermined width from the edge thereof to form a band-like exposed membrane portion 6. Connector joists 8 are disposed in a lattice-like pattern within the interior of an outer wall 7 of ordinary steel plate so as to be in conformity with the size of the liquid-tight panels 1 and are secured to said outer wall through stay plates 9. The adjacent edge portions 10 of such liquid-tight panels 1 are placed on one of the joists 8, and a connector patch member 12 is bonded to the outer side of said adjacent edge portions 10 over the band-like exposed membrane surfaces 6 by means of an adhesive 11. The width of the patch member 12 is such that some areas of the band-like exposed membrane portions 6 are left uncovered on both sides of the patch member 12. Fasteners such as nails 13 are driven through the patch member 12 into the wooden joist 8 through both panels 1, thereby securing the adjacent end portions 10 to the joist 8. Finally, a coating layer 14 of low temperature resistant adhesive is applied over the patch member 12 and the band-like exposed membrane surfaces 6 left uncovered on both sides of the patch member.

In FIG. 3, the numeral 15 designates a heat insulator, which is prepared either by injecting a foamable material into a space surrounded with a lattice-like enclosure defined by the connector joists 8 and stay plates

9, the outer wall 7 and the low temperature resistant liquid-tight panels 1 through openings in said lattice-like enclosure and allowing the material to foam in said space; or, by filling the lattice-like enclosure with a pre-formed heat insulator before the low temperature resistant panel 1 is secured in position.

As a result of the above construction, there is no exposed portion of the liquid-tight membranes 4a; direct contact of a low temperature liquified gas contained in the tank with the liquid-tight membranes 4a is positively prevented by the veneers 5a and the coating layers 14; and, the liquid-tight membranes 4a of adjacent panels 1 are liquid-tightly interconnected by the coating layers 14, so that there is no possibility that any liquid which has permeated the veneers 5a will leak through the junctions of the panels.

Further, when the liquid-tight panel 1 shown in the above embodiment is used, it is, of course, possible to prevent the separating and cracking of the membranes by absorbing in the exterior layer 5a the heat shock caused by direct contact between the surface of the inner wall of the tank and the low temperature liquid, and since the membranes 4a and 4b of low temperature resistant metal are symmetrically arranged with respect to the center of the panel and expand and contract approximately equally, such expansion and contraction of the membranes 4a and 4b will not result in warping the panel 1. Thus, the entire liquid-tight panel can ideally expand and contract.

In FIG. 3, single ply veneers 5a and 5b are bonded to the surfaces of the liquid-tight membranes 4a and 4b, but a laminate formed by a plurality of veneers may be bonded thereto as a heat shock absorbing material.

As for the method of interposing a membrane of low temperature resistant metal between layers of the panel, a method may be employed wherein hot pressing is carried out with a resin-impregnated paper sheet interposed between said membrane and the layer on each side of the membrane.

FIG. 4 shows a different embodiment of the invention. A liquid-tight panel 20 used in this embodiment consists of two plywood layers 21a and 21b of approximately the same thickness with a liquid-tight membrane 22 of low temperature resistant metal interposed therebetween. If such a panel 20 is applied to the embodiment shown in FIG. 3, since the thickness of the plywood 21a working as a heat shock absorbing material with respect to the liquid-tight membrane amounts to about half the thickness of the panel 20, a bandwise cutting away of the plywood 21a for placing a connector patch member on the cut away area would result in the adjacent edge portions of the panels being too thin, thus presenting a problem of strength. Therefore, as shown in FIG. 4, a connector patch member 23 is bonded directly to the surfaces of adjacent panels 20 by an adhesive, and the adjacent edge portions 25 of the panels 20 are secured to a connector joist 26 by fasteners 24. On both sides of said patch member 23, grooves 27 reaching the liquid-tight membranes 22 are provided in the plywood 21a parallel to the patch member 23. Each groove 27 is filled with a low temperature resistant adhesive 28 so as to be in contact with the liquid-tight membrane 22, and a coating layer 29 of low temperature resistant adhesive covering the patch member 23 is united with said low temperature resistant adhesive 28, thereby interconnecting the panels 20

in a liquid-tight manner without involving any problem of strength.

Further, as in the embodiment shown in FIG. 4, by placing the liquid-tight membrane centrally of the panel, it is possible to avoid heat shock caused by direct contact with low temperature liquid and, moreover, in spite of the use of a single membrane there is no possibility that warping of the plywood will take place due to the expansion and contraction of said membrane.

FIGS. 5 and 6 show other embodiments of the liquid-tight panels of the present invention. In FIG. 5, a liquid-tight panel 30 is constructed by bonding liquid-tight membranes 33a and 33b of low temperature resistant metal or synthetic resin to both sides of plywood 32 consisting of a plurality of layers of veneers 31 and then bonding a soft fibrous material 34 of suitable thickness to the outer side of one membrane 33a to form a heat shock absorbing layer. The fibrous material may be a wood fiber plate, a thick fabric, a laminated thin fabric, a rug or the like.

Although the low temperature liquid permeates the fibrous material 34 when the fibrous material 34 forms the inner surface of the tank, permeation beyond the same is prevented by the liquid-tight membrane 33a. Therefore, heat shock caused by direct contact between the liquid-tight membrane 33a and the low temperature liquid can be avoided by the fibrous material 34, so that there is no possibility of the membrane 33a coming off or cracking. Further, since the liquid-tight membranes 33a and 33b are positioned on both sides of the plywood 32 and expand and contract approximately equally, there will be no possibility that the plywood will warp as a result of the expansion and contraction of the membranes 33a and 33b.

A liquid-tight panel 40 shown in FIG. 6 is constructed by interposing two or more layers of low temperature resistant resin-impregnated paper sheets 43 between layers 41 and 42 of plywood and subjecting the assembly to a hot press process. In this liquid-tight panel, the thermal stresses produced in the liquid-tight membranes are very small as compared with the case of using a low temperature resistant metal sheet, so that the plywood will not warp. Further, the low temperature resistant resin-impregnated paper sheets 43 are easy to bring into close contact with the plywood layers, so that the production of the liquid-tight panel is facilitated.

As described above, according to the invention, an interior liquid-tight membrane layer within an exterior layer of plywood or a fibrous material makes it possible to mitigate the heat shock due to direct contact of the inner wall surface of the tank with low temperature liquid. For example, in the case where a membrane exists within plywood and there is a temperature difference of 60°C between the membrane and the plywood, changes in temperature which take place in the interior of the plywood are as shown in FIG. 7. From this it is seen that in the case of a temperature difference of about 60°C, if there is a plywood layer (heat shock absorbing layer) which is more than 3mm thick, this makes it possible to greatly mitigate heat shock. Therefore, there will be no separation or cracking of the membrane, which, in turn, contributes so much to the prevention of warping of the plywood. Further, since such membrane is internally provided, there is no possibility that the membrane will be damaged at the time of constructing the tank wall. Therefore, the handling

is easy and the construction of the tank wall can be carried out more easily and rapidly than in the case of the prior art.

We claim:

1. A low temperature liquified gas storage tank having an outer wall of steel, an inner wall of plywood panels spaced from the outer wall, and a solid heat insulating layer interposed in the space between the outer and inner walls, wherein

wooden joists attached to the inner surface of the outer wall define the depth of the space for said insulating layer;

said plywood panels each include at least one interior liquid-tight membrane layer composed of thin sheet metal or of resin-impregnated paper, and a 15 wood fiber or fabric heat shock absorbing layer, said heat shock absorbing layer forming the inner

wall surface of the tank; and, fastening means for securing adjacent edge portions of said plywood panels to the joists, said fastening means including a patch covering said adjacent edge portions and an adhesive covering the patch and covering portions of the panels adjacent to the patch.

2. A low temperature liquified gas storage tank according to claim 1 wherein each of said plywood panels includes two of said liquid-tight membrane layers symmetrically arranged cross-sectionally of the panel.

3. A low temperature liquified gas storage tank according to claim 1 wherein each of said plywood panels includes a heat shock absorbing layer forming the surface of the panel opposed to said inner wall surface of the tank.
